UNITED STATES PATENT OFFICE.

EUGEN HUWYLER, OF VIENNA, AUSTRIA, ASSIGNOR TO THE FIRM: IGNIS A.G., OF ZURICH, SWITZERLAND.

FURNACE FOR STEAM BOILERS.

Application filed April 5, 1926, Serial No. 99,834, and in Austria June 13, 1925.

The subject matter of the present invention is an arrangement for effecting an economic combustion with furnaces for steam boilers provided with steam jets above grate and which arrangement is characterized by the fact that the means for producing the steam jets are so arranged relatively to means permitting the entrance of over-grate air and are so provided with openings for the discharge 10 of the steam that all the over-grate air is forced to flow below an approximately horizontal fan-shaped steam blanket or stratum and along the fire bed and to intimately mix thereby with the heating gases and to cause 15 their complete combustion before they reach the heat interchange elements of the boiler.

The formation of smoke with steam-boiler furnaces is a sign of an incomplete combustion and the cause thereof is a lack of air and 20 the consequence a smaller output of the steam boiler.

The arrangement according to the present invention overcomes these drawbacks and by the particular arrangement and design of the 25 steam distributing means a supply of over-grate air, preferably in a small excess quantity, is effected by which all the combustible gases are ignited and burnt so that the highest possible temperature in the furnace is generated as well as a complete combustion of the 30 particles forming the smoke.

The efficiency is further increased inasmuch as the heating gases are prevented by the horizontal steam fan from the ineffective 35 heating of the lateral walls of the furnace and the gases reach the elements of the boiler without any appreciable loss of heat.

Preferably the steam distributing means are provided besides with the row of apertures 40 for the jets forming the horizontal steam fan with a row of apertures arranged at right angles to the first mentioned row of apertures.

Constructional examples of the subject matter of the present invention are illustrated 45 on the accompanying drawings, in which:

Fig. 1 shows a vertical section through the furnace of a water tube boiler,

Fig. 2 is a section along line II—II in Fig. 1,

Fig. 3 is a vertical section through the fire box of a locomotive,

Fig. 4 is a section along line IV—IV in Fig. 3, and

Figs. 5 and 6 show details of the steam distributing means.

Fig. 7 is a front view of the surface of the head 2 developed to show the different sizes of the steam holes or nozzles therein.

Referring now to the constructional example illustrated in Figs. 1 and 2 steam distributing means in the form of a nozzle 2 having a row of radially arranged apertures 3 are arranged directly below the roof 1 of the furnace chamber. The centre lines of the apertures 3 for the steam jets A are directed 60 towards the lateral walls 4 of the furnace chamber and the centre lines of the apertures 3¹ for the steam jets C are directed towards the end 5 of the grate. The points of intersection of all the direction lines are situated 65 above the fuel bed 6 and all the steam jets leaving the apertures 3 and 3¹ form an approximately horizontal steam fan or veil. 70 denotes a tube for supplying steam to the nozzle 2. 75

The supply of over-grate air to the furnace chamber is preferably effected by means of a channel 8 arranged within the walls of the boiler brickwork, a gate 9 being provided to control the quantity of over-grate 80 air passing through said channel.

The diameter of the apertures 3 is larger than that of the apertures 3¹.

The manner of working of the above described arrangement is as follows: 85

As the temperature inside the furnace chamber is much higher than that of the steam jets A and C leaving the nozzle 2, these jets are heated and their expansive power is increased. Owing to the larger bores by which 90 they are formed and to their shorter length the lateral steam jets A have a stronger effect than the jets C which are longer and weaker. As the lateral steam jets A bound heavily against the lateral walls 4 the heating 95 gases rising from the firebed cannot flow along these walls in the upward direction but are forced to flow below the weaker middle jets C directed towards the end of the grate and to rise along the water tubes 100 10 of the boiler. During this flow they intimately mix with the heating gases and cause the complete combustion of the latter so that they transmit their whole heating power to the water tubes. 105

The nozzle 2 is arranged beyond the end of the channel 8 and immediately below the roof 1 of furnace chamber in order to prevent the over-grate air entering the furnace through the channel 8 or eventually through 110

the fire door 11 to pass between the roof 1 and the steam jets A and C.

With the constructional example illustrated in Figs. 3-6 the steam distributor or nozzle 2 is provided besides with the apertures 3 and 3¹, which form a horizontal row of apertures for producing an approximately horizontal fan-like blanket or stratum of steam as in the first constructional example, 10 with a second row of apertures 12 arranged at right angles to the first row of apertures. The two rows of apertures of the nozzle form a T and the steam jets leaving the nozzle form a steam fan of an approximately T-shaped cross-section. The over-grate air enters through the opening 11 of the fire door flowing through a channel 13 ending below the floor of the driver's cab of the locomotive. As the steam nozzle is arranged 20 above the fire door, i. e. above the entrance opening for the over-grate air, the bulk of the latter, which is sucked through the opening of the fire door by the action of the blast pipe, is forced to flow below the approximately horizontal steam fan A and to both 25 sides of the vertical steam fan D and to intimately mix thereby with the heating gases.

The efficacious expansion of the particles of steam projected by the vertical steam fan 30 against the fire bed increases essentially the intimate mixing between the overgrate air and the heating gases and contributes to obtaining an economic combustion.

The arrangement illustrated in Figs. 3-6 in connection with a locomotive boiler may 35 be utilized for any flue boiler.

I claim:

1. In a steam boiler furnace, a grate, nozzle means above the grate having a horizontal row of radially disposed apertures, means 40 to supply boiler steam to said nozzle means, the diameter of the apertures directed toward the lateral walls of the furnace chamber being larger than the diameter of the apertures directed toward the end of the 45 grate to form a substantially horizontal film-like blanket or stratum of steam over the grate, and means to admit over-grate air below said blanket or stratum.

2. In a steam boiler furnace, a grate, nozzle means above the grate having a horizontal row of radially disposed apertures, means 50 to supply boiler steam to said nozzle means, the diameter of the apertures directed toward the lateral walls of the furnace chamber 55 being larger than the diameter of the apertures directed toward the end of the grate to form a substantially horizontal film-like blanket or stratum of steam over the grate; means to admit over grate air below 60 said blanket or stratum, and means to regulate the quantity of over grate air.

In testimony whereof, I have signed my name to this specification.

EUGEN HUWYLER.
